(57) **CLAIM**

The ornamental design for a folder with panels, as shown and described.

DESCRIPTION

FIG. 1 is a front perspective view of a folder with panels showing my new design in an unfolded configuration; FIG. 2 is a front perspective view of the folder with panels shown in partly folded configuration;

FIG. 3 is a rear perspective view thereof;

FIG. 4 is a front perspective view of the folder with panels shown in a folded configuration;

FIG. 5 is a rear perspective view thereof;

FIG. 6 is a front elevational view thereof;

FIG. 7 is a right side elevational view thereof;

FIG. 8 is a rear elevational view thereof;

FIG. 9 is a left side elevational view thereof;

FIG. 10 is a top plan view thereof; and,

FIG. 11 is a bottom plan view thereof.

The broken lines shown in the drawings show portions of the folder with panels that form no part of the claimed design. The folder with panels is shown with a symbolic break in its length. The appearance of any portion of the folder with panels between the dot-dash break lines forms no part of the claimed design.
